UNITED STATES PATENT OFFICE

171,752

CUSHION

James H. Dardenelle, Lindsay, Calif.

Application June 15, 1953, Serial No. 25,501

Term of patent 14 years

(Cl. D3—9)

To all whom it may concern:

Be it known that I, James H. Dardenelle, a citizen of the United States, residing in the city of Lindsay, county of Tulare, and State of California, have invented a new, original, and ornamental Design for a Cushion, of which the following is a specification, reference being had to the accompanying drawing, forming a part thereof.

Fig. 1 is a perspective view of a cushion showing my new design;

Fig. 2 is a top plan view thereof;

Fig. 3 is a side elevational view thereof;

Fig. 4 is a bottom plan view thereof;

Fig. 5 is a front elevational view thereof; and, Fig. 6 is a rear elevational view thereof.

I claim:

The ornamental design for a cushion, as shown.

JAMES H. DARDENNELLE.
